INVENTOR.

VERNICE MEYERS

BY *Adam E. Fisher*

ATTORNEY.

UNITED STATES PATENT OFFICE.

VERNICE MEYERS, OF THREE OAKS, MICHIGAN.

DESIGN FOR AN ELECTRIC-LIGHT STAND.

58,394.

Specification for Design.

Patented July 12, 1921.

Application filed December 2, 1920. Serial No. 427,913. Term of patent 14 years.

To all whom it may concern:

Be it known that I, VERNICE MEYERS, a citizen of the United States, residing at Three Oaks, in the county of Berrien, State of Michigan, have invented a new, original, and ornamental Design for Electric-Light Stands, of which the following is a specification, reference being had to the accompanying drawing, forming a part hereof.

The figure is a perspective view showing my new design.

I claim:

The ornamental design for an electric light stand, as shown.

VERNICE MEYERS.

Witnesses:

MORRIS G. McGAWN,
ANNA MEYERS.
